UNITED STATES PATENT OFFICE.

WILLIAM A. HARRIS, OF GREENVILLE, SOUTH CAROLINA.

HOEING-MACHINE.

No. 888,327.

Specification of Letters Patent.

Patented May 19, 1908.

Application filed November 21, 1907. Serial No. 403,221.

To all whom it may concern:

Be it known that I, WILLIAM A. HARRIS, a citizen of the United States, and a resident of Greenville, in the county of Greenville and 5 State of South Carolina, have invented certain new and useful Improvements in Hoeing-Machines, of which the following is a specification.

My invention is an improvement in hoeing 10 machines, especially designed for chopping cotton, and particularly in that class of such machines illustrated in my former patent No. 873,543 dated Dec. 10, 1907. The present invention relates to means for gaging and 15 regulating the depths of the hoes, means for securing the regulation of the size of the stand left by the hoeing devices, means for shifting the carrier frame laterally along the drive shaft, and other improvements as will 20 be specifically described hereinafter.

In the drawings Figure 1 is a top plan view 25 of a machine embodying my invention. Fig. 2 is a sectional side elevation on about line 2—2 of Fig. 1. Fig. 3 is a vertical section on about line 3—3 of Fig. 2. Fig. 4 is a detail section on about line 4—4 of Fig. 2, illustrating the guide in which the front end of the carrier slides laterally. Fig. 5 is a perspective view showing portions of the carrier 30 frame, hoe frame and hoe shaft. Fig. 6 is a detail section on about line 6—6 of Fig. 1. Fig. 7 is a detail section of a part of the revolving hoe showing the adjustable arms for 35 regulating the size of the bunch or stand, and Fig. 8 is a sectional view illustrating a somewhat different construction from that shown in Fig. 7.

In the present machine, I provide a main frame A, to which the tongue may be secured 40 and in which main frame is journaled a drive shaft B, which may be driven in any suitable manner, preferably by means of a wheel B' secured thereto, the opposite wheel B² being loose on the shaft to facilitate the turning of 45 the machine. On this drive shaft B is pivoted at its rear end a carrier frame C, which frame is slidable along the drive shaft so it and the parts carried thereby may be adjusted to any desired position, and it also 50 rocks on the drive shaft so that one end of the carrier frame and the parts carried thereby may be raised and lowered in the manner more fully described hereinafter. This carrier frame C supports at its rear end the culti- 55 vating plows D, the beams F carrying the said parts being pivoted at their front ends in con-

nection with the carrier frame and provided with a lever F', whose detent F² engages with the rack F³ on the carrier frame whereby to secure the plows in any desired adjustment up or down independent of the rocking of the carrier frame upon the drive shaft. The carrier frame may be shifted along the drive shaft to any desired position in order to perfectly align the hoeing devices presently described with the row to be hoed. The parts so far described may in general respects be similar to the corresponding parts in the machine described in my former application before referred to.

For adjusting the carrier frame C laterally along the drive shaft, I prefer to provide the said frame with a rack C' extending parallel to the drive shaft and engaged by a pinion G' on a steering shaft G, journaled in suitable bearings supported from the main frame so the said steering shaft may be turned by its wheel G² to adjust the carrier frame laterally to any desired position upon the drive shaft. The rack C' is extended at C² for engagement 80 by a detent pawl C³, carried on the main frame and which may be adjusted into engagement with the rack in order to secure the same and the frame C in any suitable position upon the drive shaft.

The carrier frame is pivotally and slidably mounted at its rear end upon the drive shaft and has at its front end a roller C¹³, which operates within a supporting frame C⁵ adjustably held at one end C⁶ to a slotted bracket C⁷ depending from the front bar of the main frame and adjustable at its other end C⁸ along a bracket C⁹ depending from the front bar of the main frame, and having a plurality of openings C¹⁰ through which the bolt C¹¹ may be passed in securing the end C⁸ of the supporting frame in any suitable adjustment up or down. By this means the carrier frame may be adjusted at its front end to properly level the hoes of the chopper frame, this being especially useful in adapting the machine to the height of the draft animal hitched to the machine, in the practical operation of the invention. The hoeing frame I is pivoted at one edge I' on an axis approximately in line 105 with the direction of the motion of the machine, and at its opposite edge has bearings I² for the supporting shaft of the chopping hoes.

In pivoting the hoeing frame it is preferred 110 to provide the carrier frame C with a lower forwardly projecting arm C²⁰ whose front

end is upturned providing the bearing at I' for the front end of the hoeing frame I, the pivot at the rear end of the hoeing frame being effected by means of the countershaft J which is journaled in the hoeing frame and extends at its rear end through the said hoeing frame and into a bearing at I² in the carrier frame C. The hoeing frame is provided with an arch I³, which extends over the countershaft J, and is provided at its front end with a trunnion I⁴ which forms the forward extension of the carrier frame and to which the roller C³ is journaled, as will be understood from the drawings.

15 The countershaft carries a pinion J' and a sprocket wheel J², the pinion J' being movable along the countershaft and adapted to be secured in any adjustment thereon so it can be set into and out of engagement with any desired rack K', K² or K³ of the gear K, which is keyed to the drive shaft and movable along the same with the carrier frame C so it will always be in position to mesh with the rack on the counter-shaft.

20 By this construction the drive shaft through its rack wheel gives motion to the pinion on the countershaft, and the sprocket wheel on the countershaft gives motion by the sprocket chain J³ to the hoe shaft L which is journaled in the bearings I² at the swinging end of the hoeing frame. The hoeing frame swings up and down at its swinging edge and is partially supported at such edge by a spring M connected at its upper end with the upright M' on the carrier frame and at its lower end with the swinging end of the hoeing frame so it will aid in supporting the weight of said frame, and a lever M² is secured to the hoeing frame and moves along the arc M³ on the carrier frame, said arc having a stop at its lower end to limit the downward movement of the lever and the hoeing frame and being provided with one or more notches M⁴ for engagement by the pawl M⁵ of the lever in order to hold the hoeing frame up clear of the ground.

25 The hoeing frame is provided at its front end with a gage wheel N adjustably supported in the manner presently described and adapted to limit the extent to which the hoes may operate in the ground. This gage wheel N has an upright N' adjustably connected with a bracket N², which bracket N² rocks relatively to the hoeing frame so it can be adjusted with respect thereto and may be secured in any suitable adjustment by the clamping devices N³. As shown the hoeing frame has its front arm provided with a boxing N⁴ forming a bearing for the front end of the hoe shaft and secured to the hoeing frame by a clamping device N⁵, the bushing being extended at its ends to receive the rocking bracket, and a collar N⁶ being fitted on the front end of the hoe shaft in advance of the bushing to secure the hoe shaft from

endwise adjustment. By the described construction, it will be noticed the bracket may be adjusted relatively to the hoeing frame in order to accommodate the angle of the gage wheel to the angle of the said hoeing frame and the gage wheel may be set up or down to regulate the depth at different angles, as may be desired in the operation of the invention.

30 By preference the bracket N² is mounted midway between its ends on the bushing and supports at its opposite ends the listers O, the upright O' of one of the listers being adjustably connected with the standard of the gage wheel and the upright O² of the other 35 lister being adjustably connected with the end of the bracket opposite that supporting the gage wheel, the adjustment of the lister standards being effected by the slotting of the same to receive the securing bolts, as shown in the drawings.

35 The hoes P are supported by their arms P', P², on the hoe shafts and revolve therewith. The arms P' may be in fixed relation and with a uniform space between the hoes of the fixed arms and at intervals preferably two blades of the hoes are adjustable in the direction of revolution so that I may set these adjustable hoes toward and from the adjacent ones. This operation is important 40 as if the hoes were of such length and so spaced apart as to operate when uniformly placed to cut out the entire cotton row, one or more of the hoes might be either advanced or retracted to increase the space in the direction of revolution between the hoe blades and thus leave a stand of the size corresponding to the extent to which the said blade or blades were advanced or retracted. As shown in Figs. 3 and 7 this is preferably 45 effected by making two of the arms P² adjustable in the direction of revolution by pivoting them at their inner ends concentrically with the hoe shaft and having them secured between their ends adjustably in 50 connection with the curved bars P³, slotted at P⁴ to receive the securing bolts P⁵. In this construction the two adjustable hoe arms are independent and made adjustable independently. It may, however, be preferred to adjust the diametrically opposite 55 hoeing arms jointly, in which event said arms may be integral, as shown in Fig. 8 of the drawings. This is an important feature of my invention, as by it I am able by a slight adjustment of the hoe blades in a circular direction to regulate the size of the stand or bunch left in the row, and this may be accomplished in a simple manner as will be understood from the drawings, and foregoing description. By properly spacing both of the adjustable arms of the hoe, two bunches may be left for each revolution of the hoe, or if it is desired to space the bunches further apart, one hoe may be ad-

justed equidistantly between its adjacent hoes, and the other properly set to secure the desired size of bunch, or any suitable number of blades of the revolving hoe may 5 be made adjustable, as will be understood.

I claim—

1. A revolving hoe having a series of blades and arms supporting the same and rigid with each other and provided with 10 curved slots, blade supporting arms movable relatively to the other arms of the hoe, and bolts extended from said movable arms through the curved slots of the bars for securing the movable arms in different adjustments.

2. The combination of a main frame, a hoe frame swinging laterally in the main frame, a gage wheel and listing devices, and a support therefor adjustably connected with the 20 laterally swinging hoe frame whereby it may be set to properly support the gage wheel and listing devices in different adjustments of the laterally swinging frame.

3. A revolving hoe having a hoe shaft, a plurality of blades one or more of which are pivoted at their inner ends concentric with the hoe shaft and adjustable in the direction 25 of revolution of the hoe.

4. The combination of a main frame, a 30 drive shaft, a carrier frame sliding along and rocking on the drive shaft, a toothed rack connected with the carrier frame, a steering shaft having a pinion meshing with the said rack, bearings for said shaft, hoeing devices 35 supported by the carrier frame, and means for adjusting the hoeing devices in the carrier frame.

5. The combination with the carrier frame, of a hoeing frame pivoted at one edge to the 40 carrier frame, hoeing devices supported at the swinging edge of the hoeing frame, a spring support for the swinging edge of the hoeing frame, and gage devices for regulating the depth to which the hoeing devices 45 may be operated in the ground.

6. The combination of the carrier frame, a laterally swinging hoeing frame pivoted at one edge to the carrier frame whereby its other edge may swing up and down the said 50 hoeing frame swinging at a right angle to the direction of draft, hoeing devices at the swinging edge of the hoeing frame, and a gage wheel supported at such edge of the hoeing frame.

55 7. A hoeing machine comprising a laterally swinging hoeing frame pivoted at one edge

whereby it may be swung up and down at the other edge, hoeing devices at the swinging edge of the hoeing frame, and a gage wheel at such edge of the frame.

60

8. In a hoeing machine a hoeing frame pivotally supported at one edge whereby its other edge may swing up and down, hoeing devices at such edge of the frame, a gage wheel, a bracket having a rocking connection with the swinging edge of the hoeing frame, means for securing the said bracket in different adjustments relative to the hoeing frame, and means for securing the gage wheel in different adjustments upon the said 70 bracket whereby the gage wheel may be set at different levels, and the bracket may be adjusted to support the said gage wheel in proper relation to the ground surface.

9. A swinging hoeing frame provided at 75 its swinging edge with a rocking bracket and a gage wheel supported on said bracket.

10. A swinging hoe frame provided at its swinging edge with hoeing devices, a bracket having an adjustable connection with the 80 swinging edge of the hoeing frame, and a gage wheel adjustably supported on said bracket.

11. A swinging hoe frame provided at its swinging edge with an adjustable bracket, 85 and gage and listing devices supported on said bracket.

12. A swinging hoe frame provided at its swinging edge with a bracket rocking midway between its ends in connection with the 90 hoe frame, listing devices at the opposite ends of the bracket, and a gage wheel supported on said bracket, said gage wheel and listing devices being adjustable relative to the bracket.

95

13. In a hoeing machine, a laterally swinging hoe frame, hoeing devices at the swinging edge of said frame, a gage wheel and a support for said wheel adjustably connected with the hoe frame.

100

14. A hoeing machine comprising a main frame, wheels supporting the same, a hoeing frame pivotally supported at one edge on an axis approximately parallel with the direction of draft and swinging laterally, and hoeing devices carried by said laterally swinging frame substantially as set forth.
